UNITED STATES PATENT OFFICE.

ROBERT HARRY ROBERTS, OF SAN ANTONIO, TEXAS.

SWITCH-POINT SHIFTER.

SPECIFICATION forming part of Letters Patent No. 764,867, dated July 12, 1904.

Application filed April 2, 1904. Serial No. 201,343. (No model.)

To all whom it may concern:

Be it known that I, ROBERT HARRY ROBERTS, a citizen of the United States, residing at San Antonio, in the county of Bexar and 5 State of Texas, have invented certain new and useful Improvements in Switch-Point Shifters; and I do hereby declare the following to be a full, clear, and exact description of the invention, such as will enable others skilled in

10 the art to which it appertains to make and use the same.

This invention relates to devices for shifting the points of railroads; and it consists in the novel construction and combination of 15 the parts hereinafter fully described and claimed, whereby the points may be operated from the car.

In the drawings, Figure 1 is a side view of the end portion of a car, showing the point-shifting mechanism. Fig. 2 is a plan view of 20 the same.

A is the end portion of a street-car of any approved construction.

B is the point of a switch such as commonly 25 used on street-railroads.

C is a bracket or frame which is secured to the end portion of the car-frame. D is an operating-rod which is supported by the said bracket and provided with a blade d at its 30 lower end. The blade has a tapered edge d' at its bottom for engaging with the point. The bracket has a hole e in its lower part, in which the rod can move freely in all directions.

G is a spiral spring which encircles the rod 35 D and which has its upper end rigidly secured to the rod. The lower end g of the spring is secured to the bracket near the hole e. The upper part C' of the bracket has a slot h arranged crosswise of the switch-point, and the 40 rod D projects through this slot. The upper

end of the rod D is provided with an operating-handle i, which is preferably arranged in line with the blade. The spring normally supports the blade, and the device is operated by the motorman, who depresses the rod into 45 engagement with the switch-point and shifts the point by a dexterous manipulation of the blade without getting down from the car.

What I claim is—

1. In a switch-point shifter, the combination, with a bracket rigidly secured to the car, of a depressible operating-rod mounted in the said bracket and provided with a shifting device at its lower end for engaging with the point, and a spiral spring encircling the said 50 rod, one end of the said spring being secured to the said bracket and the other end to the said rod, said spring operating to raise the rod and permitting it to be moved axially and laterally. 55

2. In a switch-point shifter, the combination, with a bracket rigidly secured to the car and provided with a lower part having a hole and an upper part having a slot arranged crosswise of the point, of a depressible operating-rod arranged loosely in the said hole and slot and provided with a shifting device at its 60 lower end for engaging with the point, and a spring secured to the said lower part of the bracket and to the said rod above the said 65 lower part, said spring operating to raise the rod and permitting it to be moved axially and laterally. 70

In testimony whereof I have affixed my signature in the presence of two witnesses.

ROBERT HARRY ROBERTS.
